UNITED STATES PATENT OFFICE.

CHARLES G. NESSLER, OF NEW YORK, N. Y.

APPARATUS FOR WAVING HAIR.

Application filed September 22, 1922. Serial No. 589,744.

This invention relates generally to apparatus for curling or waving hair.

In the art of the so-called "permanent waving" of hair as heretofore known it has been the practice to divide up the hair into locks or strands each of which has been wound on a supporting or core member and wrapped either in wound absorbent material, or a composite-envelope, bag, pad or packing containing solidified borax and water. The strand of coiled hair enclosed in its thick and moistened covering has then been inserted in a non-metallic tube to which heat was externally applied for a sufficient time to penetrate through the wrapping and to heat and soften the hair strand and cause it to assume in more or less permanent form, the waved formation by which it was characterized when coiled within the tube.

Although the described method of hair treatment has gone into extensive use, it is open to a number of objections. The relatively thick composition envelopes or pads in which the coils were enclosed before insertion in the tubes, required the use of a relatively considerable amount of water in order to properly moisten the borax contained therein and to this was added the water of crystallization of the borax which is released when heat is applied. The result was that an excessive quantity of heated water and steam was produced in the tube. This liquid was not only difficult to control and restrain from escaping from the tube into scalding contact with the head of the customer, but a substantial period of time was required to heat the coil of hair through the resisting heat insulating layer provided by the thick bag or pad as well as to bring the relatively large quantity of water and borax to the required temperature. The excessive time thus consumed is not only wasteful but it is a considerable source of annoyance and discomfort to the person whose hair is being treated.

An additional disadvantage of the apparatus used in prior methods has consisted in the use of a uniform and standard size of coil receiving tube, the fixed size being such that each tube was adapted to receive the largest size lock or strand likely to be treated and was substantially larger than was required for the treatment of numerous shorter and smaller locks formed of the thinner portions of the hair growth.

The use of a container tube having both a greater diameter and a greater length than the size of the contained coil resulted in a wasteful expenditure of energy and time in bringing the contents of the tube to the required degree of temperature, because of the heat insulating effect of the unfilled air spaces within the tube.

It is the general object of the present invention to provide hair waving apparatus which will be free from the objections referred to.

The invention includes the provision of coil container tubes of various sizes in order to provide tubes relatively closely fitted to the individual coils. This results in the substantial elimination of air space between the coils and the inner surfaces of the enclosing tubes. I still further facilitate the carrying out of the coil heating operation by doing away with the relatively thick pads or their equivalent which have heretofore been used. Instead the moistened coils are inserted into the tubes either without covering of any character or each coil is wrapped with a strip of moistened fabric or like material which offers negligible resistance to the passage of heat therethrough from the tube to the coiled strand being treated.

In a preferred form of the invention the coil covering strips are impregnated with a suitable hair softening material in liquid form and then dried for convenient preservation and storage. When about to be used a covering strip containing the softening agent incorporated therein in the form of a relatively imperceptible dry deposit, is moistened in a measured amount of water or other solvent, a portion of which may be used to directly moisten the coiled hair itself. The moistened strip, wrung out to avoid the use of an excessive amount of moisture in the tube, is then wrapped in position on the coil and the wrapped coil inserted in the heater tube. The particular softening agent employed forms no essential part of the invention herein described and claimed and the method in which the softening agent is employed forms the subject matter of a companion application.

The invention contemplates also the use of heater devices provided with a standard size bore and which will receive tubes of smaller diameter than the bore either fitted within each other in progressively decreas-

ing sizes until the strand of hair is fitted, or a single tube approximately the size of the strand and held in place in the relatively larger bore of the heater by any suitable holding means. In addition suitable means are employed for adapting the length of the container chamber to the length of the wound strand.

In the drawings in which a number of 10 embodiments of the invention have been selected for illustration,

Figure 1 is a view in longitudinal section of a hair waving device embodying the invention.

15 Figure 2 is a view partly in section and partly in elevation of the device shown in Figure 1 and showing the use of an adapter tube.

20 Figure 3 is a view partly in section and partly in side elevation of a core member on which a lock of hair is wound for treatment.

Figure 4 is a view in side elevation of a modified form of core member.

25 Figure 5 is a view in longitudinal section of an adapter tube forming part of the invention.

Figure 6 is a view similar to Figure 1 showing a modified form of core member and end closure member.

30 Figure 7 is an end view of the device shown in Figure 1.

Figure 8 is a view in perspective of the closure device shown in Figure 6.

35 Figure 9 is a view in side elevation of a heater device equipped with a modified form of end closure means.

Figure 10 is a view in section of the end portion of a heater device equipped with still another form of closure means.

40 Figure 11 is an end view of the device shown in Figure 10 in open and closed positions.

Figure 12 is a view in side elevation of the closure means shown in Figures 10 and 11.

45 Figure 13 is a view similar to Figure 12 of still another form of closure.

Figure 14 is a view in section of the end of a heater device equipped with the closure member shown in Figure 13.

50 Figure 15 is a view of a modified form of the invention showing a standard size heater and relatively smaller heater tube.

Figure 16 is a view of the device shown in Figure 15 in disassembled relation.

55 Referring to the drawings for a more detailed description of the invention, in Figure 1 is shown a hair-waving device embodying the invention and including a core member 10 about which a strand of hair 11 may be coiled to provide a waved formation of the hair. A tubular heater tube 12 having its inner diameter substantially equal to the external diameter of the wound strand of hair is adapted to have the strand 11 supported by the core member 10 inserted there-

in. The coiled strand 11 may have a strip of flannel or other flexible sheet material 13 wound thereabout in enclosing relation to prevent actual contact of the strand with the inner surface of the heater tube 12 if 70 desired.

The core members 10 are preferably formed in variable lengths to correspond to the different lengths of the hair strands to be treated and are provided with terminal 75 members 14 closely fitting the internal diameter of the heater tubes to thereby form a strand-receiving chamber in the tube closely approximating the length of the coiled strand. The other end of the strand supporting member 10 is preferably slotted as at 15 to provide means for conveniently attaching the member 10 to the strand through the use of a section of cord 16 which is tied in place around the strand and 80 through the slot.

85 The heater tube 12 may be fitted permanently or removably in place in the bore of a heating device 17 supplied with an electrical heating coil 18 having connection as at 90 19 with a source of current. The heating device 17 is preferably supplied with a hollow cool handle member 20 and manually movable handle members 21 which form extensions of arms 22 fulcrumed at 23 and 95 carry gate or closure members 24 adapted to cooperate with the end of the heater tube adjacent the scalp of the customer to open or close the tube, and grip the lock or strand of hair and hold the heater in place thereon. The closure members 24 may be covered with 100 felt or other non-heat conducting material and felt sleeves 25 may be fitted to the ends of the tubes 12 to prevent discomfort to the customer by application of the heated tubes 105 to the hair adjacent the scalp.

110 In Figure 2 of the drawings, the use of an inner heater tube 26 is shown in order to fit the internal diameter of the heater tube to the external diameter of the coiled 115 strand. The tube 26 closely fits the internal diameter of the main heater tube 12 and may itself receive one or more tubes fitted into each other to fit the coiled strand and reduce to a minimum the air space surrounding the coil within the tube. In Figure 5 is shown one of the adapter tubes used for this purpose.

120 In Figure 4 of the drawing is shown a modified form of strand supporting member 126 27 which is substantially longer than the member 10, and instead of being provided with the terminal member or button 14 is provided with a stop or plug member 28 adapted to be moved along the rod 27 to 125 adjust the length of the strand receiving chamber in the tube to the length of the coiled strand received thereon.

130 In Figure 6 of the drawing there is shown an embodiment of the invention in which a 130

hair supporting member 30 is used having a stepped tapered formation to provide a like external diameter of the coiled strand at all sections of its length regardless of the varying thickness of the strand itself. A support of this shape compensates for variations in the thickness of the strand, as will be clear, and facilitates the heating operation by maintaining a uniform relation between the heater tube and the enclosed strand.

There is also shown in this figure and in Figures 7 and 8 a modified form of tube closure or gate. This closure takes the form of two spring members 31 attached at one extremity as at 32 to the heater tube 12 and carrying the gate members 33 at their outer and free ends. Normally the spring members 31 tend to hold the gate members 20 in their separated or open position as indicated in Figure 8 of the drawings. A ring member 34 having an elliptical formation may be turned to bring its short axis into closing engagement with the spring members 31 as in Figure 7 or with its long axis alined with the spring members to permit the gate members to open, as in Figure 8.

In Figure 9 of the drawings, a tube closure device is shown which is similar to the one shown in Figure 2 except for the disposition of the handle members 21 and an overlapping relation of the gate members 24 to provide an effective liquid-tight closure for the tube. One side of one end of the tube 12 is preferably cut away to provide a seat for the underlying gate member 24 at the left as shown in this figure.

In Figures 10, 11 and 12 there is shown another form of closure means in which the gate members 35 are hinged together at 36. A clip member 37 carried by one of the gate members 35 is arranged to clasp a wall of the tube 12 and hold the closure in place on the end thereof.

In Figures 13 and 14 is shown still another form of gate or closure in which the gate members 38 are each provided with a clip member 39 having projecting stems 50 adapted to be inserted inside the end of the tube 12 to hold the closure closed and in place.

In Figure 15 of the drawings there is shown a heater device 41 of a relatively short form and having a bore opening 42 sufficiently large to take the largest size heater tube that is employed in practice. The heater tubes employed with the heating device shown may be relatively smaller than the size of the bore of the heater and a friction spring member 43 mounted on the side of the tube frictionally engages one side of the bore 42 to hold the heater and the tube in the correct relation for effective operation. A covering or wrapping as at

44 on the exposed end of the tube forms a convenient cool handle. Any form of closure device as the gate members 33 may be used to seal the scalp-engaging end of the tube. A suitable cap or plug 45 may be used to seal the opposite end of the heater tubes shown in the various figures of the drawings.

My present improvements are particularly adapted for the process of permanent waving of natural hair on the human head, and they serve to materially shorten the time heretofore required in this work and also to greatly lessen the discomforts which the subject has heretofore necessarily been required to undergo. My improvements also minimize the chances of injuring or impairing the hair structure, which impairment is likely to occur in the heretofore practiced processes.

What I claim is:

1. In hair waving apparatus, a support for a wound hair-strand, a hair strand heater tube formed of heat conducting material and having an internal diameter substantially equal to the external diameter of the strand to be treated therein, and having its internal length adjustable to agree substantially with the length of wound strand when mounted thereon, said length adjusting means being arranged upon said support.

2. In hair waving apparatus, a heater-tube and a set of hair-strand adapter tubes each having different internal dimensions whereby strands of different sizes can be fitted to selected heater tubes of corresponding size.

3. In hair waving apparatus, a heater-tube, a plurality of adapter tubes having different internal dimensions adapted to be selected to closely fit strands of correspondingly different sizes.

4. In hair waving apparatus, a strand heater tube having internal dimensions to substantially fit strands of a certain size, and a series of adapter tubes of smaller size arranged to be placed within the heater tube to fit wound strands of smaller size.

5. In hair waving apparatus, a strand heater tubes having a certain length, a support for the wound hair-strands and means carried by said support and insertible in the tube and adjustable axially thereof to regulate the length of the strand receiving chamber in the tube and closely fit the same when so adjusted.

6. In hair waving apparatus, a strand heater tube having an internal diameter to substantially fit strands of a certain outside diameter, adapter tubes arranged to be fitted within the heater tube to fit strands of smaller diameter, and capable of being nested in operation, a support for the wound hair-strand, and plug means mounted on said support and for sealing the tube and adjust-

able longitudinally of the adapter tubes to regulate the length of the strand receiving chamber to seal it to accord with the length of the strand.

- 5 7. In hair waving apparatus, a heater tube adapted to receive a strand of hair to be treated, an elongated member adapted to have a strand of hair attached thereto at one end and to have the strand coiled thereon
- 10 for treatment, and adjustable means carried within the heater-tube by the elongated member at the free end of the supported strand for closing the tube at a selected point therein to form the end of a strand
- 15 receiving chamber.
8. In hair waving apparatus, a heater tube adapted to receive a strand of hair to be treated, an elongated member adapted to have a strand of hair attached thereto at one end and to have the strand coiled thereon for treatment, and means carried by the elongated member for closing the tube to form the end of a strand receiving chamber, said tube closing means being movable along 25 the elongated member to form the chamber end at the end of the strand.
9. In hair waving apparatus including a heater tube, closure means for the end of the tube comprising pivotally connected members, constructed and arranged so as to provide a substantially central opening through

which a strand of hair may pass into said heater tube, one of said members being provided with a clip having spring actuated clamping means for mounting the closure 35 means in operative position on said heater tube.

10. In hair waving apparatus including a heater tube, closure means for the end of the tube comprising pivotally connected 40 members constructed and arranged so as to provide an opening through which a strand of hair may pass into said tube, one of said members being provided with spring jaws for engaging the wall of the tube at the end 45 to hold the closure in operative position.

11. In hair waving apparatus including a heater tube, closure means for the inner end of said tube comprising pivotally connected members constructed and arranged so as to 50 provide an opening for the passage therethrough of a strand of hair, one of said members being provided with spring jaws comprising a strip of resilient metal doubled twice on itself with one free end anchored 55 to one of said members and the other free end acting as a spring jaw for engaging the wall of said tube to hold the closure in place.

Signed at New York, in the county of New York and State of New York this fifteenth day of September A. D. 1922.

CHARLES G. NESSLER.
